UNITED STATES PATENT OFFICE.

EDGAR GRANVILLE XANDER, OF MANSFIELD, OHIO.

DISINFECTANT MIXTURE.

SPECIFICATION forming part of Letters Patent No. 357,259, dated February 8, 1887.

Application filed August 19, 1886. Serial No. 211,260. (No specimens.)

To all whom it may concern:

Be it known that I, EDGAR GRANVILLE XANDER, a citizen of the United States, residing at Mansfield, in the county of Richland 5 and State of Ohio, have invented a certain new and useful Improvement in Antiseptic Compounds; and I do declare the following to be a full, clear, and exact description of the invention, such as will enable others skilled in 10 the art to which it appertains to make and use the same.

The object of the invention is to form an antiseptic or disinfectant mixture which may be used in garbage barrels or vaults where the 15 garbage is kept in the houses or on the premises in cities and towns. It may, however, be employed in many other places for the same or an analogous purpose.

I take the following ingredients to make up 20 my compound, namely: charcoal, forty parts; coal-tar, four parts; copperas, one part.

The ingredients are thoroughly comminuted and then intimately mixed together. The whole is then dried and ready for use.

25 Just before opening the receptacle for the introduction of garbage a small portion of the dried mixture should be set on fire in the vault or garbage-chamber by the servant.

This will require no more trouble than the lighting of a match, and it will burn slowly, 30 emitting a smoke or vapor, which will completely neutralize any odors emanating from the garbage-receptacle.

I am aware that caustic soda, sulphate of iron, gum-camphor, and oil of tar have been 35 compounded with pulverized charcoal to form a disinfectant; also, that oak-bark, gypsum, and tobacco have been compounded with charcoal, copperas, and coal-tar to form a deodorizer; also, that tobacco, tannin, gypsum, permanganate of potassa, and gum-camphor have been compounded with charcoal and copperas, for the purpose of arresting the decomposition 40 of animal-matter; but

What I claim to be new, and desire to protect by Letters Patent, is—

A deodorizer or disinfectant mixture consisting of one part of copperas and four parts of coal-tar intimately mixed with forty parts of charcoal, as set forth.

In testimony whereof I affix my signature in presence of two witnesses.

EDGAR GRANVILLE XANDER.

Witnesses:

LOWREY SIBBETT,
JOSIAH BOYCE.
